UNITED STATES PATENT OFFICE

137,164

DESIGN FOR A MERCANDISE DISPLAY FIXTURE

Nate Peck, Newark, N. J.

Application September 1, 1943, Serial No. 111,037

Term of patent 7 years

To all whom it may concern:

Be it known that I, Nate Peck, a citizen of the United States, residing at Newark, in the county of Essex and State of New Jersey, have invented a new, original, and ornamental Design for Merchandise Display Fixtures, of which the following is a specification, reference being had to the accompanying drawing, forming part thereof.

The figure is a perspective view of a merchandise display fixture, showing my new design.

I claim:

The ornamental design for a merchandise display fixture, as shown.

NATE PECK.
